UNITED STATES PATENT OFFICE.

ALBERTO DE MÁRQUEZ, OF NEW YORK, N. Y.

PERFORATING MACHINE.

Application filed July 27, 1921. Serial No. 487,845.

To all whom it may concern:

Be it known that I, ALBERTO DE MÁRQUEZ, a citizen of Colombia, South America, residing at New York, in the county of New

5 York and State of New York, have invented certain new and useful Improvements in Perforating Machines, of which the following is a specification.

This invention relates to an electrical vibratory machine for perforating paper and other material particularly for the purpose of forming stencil designs adapted for reproduction on fabrics which are to be embroidered.

15 The present machine is not limited to the foregoing use as it can be employed as a check protector, check writer, attached to a pantograph for making stencils to be used in reproducing maps and to put to other 20 uses.

Heretofore electrical vibratory perforating devices have relied solely upon the puncturing action of a needle. Needle punctures in paper such as is commonly used for the 25 making of stencils for the reproducing of designs cause a pressing up of the paper on its under side. Consequently, after the stencil has been used a few times, the pushed up margins of the punctures formed by the 30 needle become pressed together and practically close the punctures, thereby preventing the stenciling effect from occurring at a number of points of the design and resulting in the stencil soon becoming worthless.

35 My invention dispenses entirely with the use of a pointed needle which merely punctures without forming clean cut perforations and in lieu of the well known pointed needle heretofore used, I provide a punch which 40 forms a clean cut perforation or punch hole in the paper each time the punch vibrates. These perforations, while minute, are, nevertheless, clean cut and there are no pressed up margins which fill the holes. On the other 45 hand, once the stencil is made according to the desired design, it is a permanent stencil which may be used for a large number of times and will enable a large number of stencils, all complete and distinct, to be had before the stencil wears out.

The punch is hollow and provided with an automatic clearing device to prevent the accumulation of punchings and may be combined with a spring actuated presser foot 55 adapted to bear on the paper to hold the paper down.

The machine may run directly on the surface of the paper while the latter is supported on a suitable bed such, for instance, as a piece of felt.

60 The presser foot may be provided with suitable guide faces which can run along the straight edge or rule so that straight lines may be accurately arranged.

Any suitable electrical vibratory means 65 may be employed for affording the reciprocating or vibratory motion to the punch.

Any means may be employed to regulate the rate and amplitude of vibration of the 70 punch. Electrical resistances, spring means, etc., may be used for that purpose.

75 It is to be understood, however, that the invention may be embodied in other forms than the one shown and described without departing from the essential principle involved and the disclosure is to be considered as illustrative, instead of restrictive, of the scope of the invention.

In the accompanying drawings:

Figure 1 is a vertical section of an embodiment of the machine which is adapted to run directly on the paper.

Fig. 2 is a plan view with certain parts in section, as indicated by the line 2-2, Fig. 1.

80 Fig. 3 is an enlarged section of the chuck, punch, and clearing device of Figs. 1 and 2.

Fig. 4 is a detail view of the presser foot.

The machine is carried by a base 1 having anti-friction ball casters 2 and a removable 90 cover 3. The electrical vibrator comprises a magnet 4, an interrupter 5, and an armature 6 provided with contact spring 7, of well known construction. The electrical vibrator is mounted on the base 1 and enclosed within the removable casing 3. Suitable binding posts 8 having circuit connections with the electrical vibrator, afford means for connecting the machine to wires to a battery or to an ordinary electric lamp 100 socket, in which latter case a transformer will be used.

105 A suitable controlling switch 9 is mounted on the box or casing 3 in a convenient position to be operated by the same hand of the operator which is used to move the machine to and fro whereby the operation of the machine may be controlled.

Connected to the armature 6 is the vibrating arm 10 for vibrating the punch 110 used in my invention. As will appear presently, different arrangements of punches

may be employed but in each instance the punch is vibrated by the arm 10.

The shank or stem of the punch appears at 11, the upper end of which has a detachable screw and socket connection 12 to a ball and socket joint 13 by which the complete punch is connected to the arm 10. The detachable connection 12 permits quick and easy attachment of the stem 11 or its removal 10 from the arm 10. The stem 11 is provided with a chuck 13'. A hollow punch 14 is held by the chuck 13. The lower end of this punch may be concave, as shown at 15. The stem 11 works in a guide 16 which has an 15 adjustable connection 17 with base 1.

For the purpose of clearing the punch 14 from the punchings made out of the paper from which the stem is being formed, I provide a clearing pin 18 working inside of the 20 punch 14 and having a ball and socket connection 19 with an arm 20 which is fastened at 21 to an adjustable bracket 22.

The arm 10 and stem 11 may be enclosed in a suitable tubular casing 23 if desired.

The bracket 22 is adjustably connected to the base 1 at 24 so that like the guide 16, it may be moved outwardly or inwardly as desired and secured where positioned by the screw shown.

To the bracket 22 is hinged at 25, a presser foot 26 which has a guide 27 through which the punch 14 operates. A suitable spring 28 bearing on the bracket 22 and the presser foot 26, holds the latter down upon the paper 35 so that as the machine is moved over the paper (which may be considered to be represented by the line 29, Fig. 1), the presser foot holds down the area of paper defined by the opening around the guide 27 which 40 area is to be punched, thus insuring against any pulling upwardly or displacement of the paper while the punching operation is going on.

The presser foot 26 is provided with a 45 polygonal edge composed of a plurality of straight surfaces. By placing rule or straight edge R on the paper, any one of the edges 26^a of the presser foot may be used to guide the machine so that it will form a 50 straight line extending in any desired direction.

The form of the invention shown is particularly adapted for use when the machine is to run directly on the paper being made 55 into a stencil. The ball casters 2 enable the machine to be readily pushed by hand over the paper and the presser foot 26 holds the paper down on the table. To enable the

punch to readily pass through the paper, the paper may be laid upon a piece of felt.

60

What I claim is:

1. In a machine for perforating paper or other material, the combination with a movably mounted supporting base, of an electrical vibrator carried thereby, a punch operated by the vibrator and movable with the base, said punch being adapted for cutting the perforations in the paper or other material, a presser foot having a movable connection to the supporting base aforesaid and mounted for up and down movement for engaging the paper or other material in the region where the punch operates thereon, and spring means for holding said foot down on the material being perforated.

65

2. In a machine for perforating paper or other material, the combination with a movably mounted supporting base, of an electrical vibrator carried thereby, a punch operated by the vibrator and movable with the base, said punch being adapted for cutting the perforations in the paper or other material, a clearing device which is connected to the base and is stationary in relation to said punch and is adapted for removing the 80 cuttings from said punch, and a presser foot through which the punch operates.

75

3. In a machine for perforating paper or other material, the combination with a movably mounted supporting base, of an electrical vibrator, a punch operated thereby adapted for cutting the perforations in the paper or other material, and a clearing device which is stationarily mounted in relation to said punch and is adapted for removing 90 the cuttings from said punch.

95

4. In a machine for perforating paper or other material, the combination with an electrical vibrator, of a punch operated thereby for cutting the perforations in the paper or other material, and a stationarily mounted clearing device in relation to which the punch is slidably, adapted for removing the cuttings from said punch.

100

5. In a machine for perforating paper or other material, the combination with an electrical vibrator, of a hollow punch operated thereby adapted for cutting the perforations in the paper or other material, and a stationarily mounted clearing device located inside 105 of the punch and in relation to which the punch is slidable, said clearing device being adapted for removing the cuttings from said punch.

110

In testimony whereof I affix my signature.

ALBERTO DE MARQUEZ.
